UNITED STATES PATENT OFFICE.

THOMAS R. HAYTON, OF APPLETON, WISCONSIN.

TUBE CLEANER.

Application filed December 5, 1927. Serial No. 237,737.

My invention relates to a device adapted for use in cleaning the deposits from the inner surfaces of pipes or tubes used for the transmission of paper stock and similar 5 liquid or semi-liquid bodies.

After continued use of the pipes through which paper stock is transferred, the inner surfaces of such pipes become coated by deposits and the capacity of the pipes is materially lessened. In view of the fact that these pipes are frequently quite long and have bends or turns therein, it is difficult, if not impossible, to effect their cleaning without the use of some instrumentality that 10 will be impelled through the tube by the force in the liquid therein.

To accomplish the desired result by means of simple mechanism, the device here disclosed has been employed with satisfactory 20 results. An object in the construction has been to provide for extreme simplicity and relatively certain efficiency. The essentials of the device are a frame or casing, forward guide arms rigidly connected to the casing, 25 rear guide arms having a wholly resilient connection to the frame, together with impeller blades mounted on the frame with capacity for radial movement, to accommodate themselves to variations in diameter 30 and inequalities in the pipe.

The device of my invention will be more readily understood by reference to the accompanying drawing, in which—

Fig. 1 is a vertical sectional view through 35 a device constructed in accordance with my invention, it being shown in position in a pipe or conduit, and

Fig. 2 is an end view of the parts with the rear guide arms and connection removed.

In the drawings, the device is illustrated 40 in position in a large conduit for paper stock. It comprises a frame 10, having a concentric internally threaded hub or boss 11. Projecting horizontally from the side 45 of the frame opposite to that on which the hub 11 is located are spaced lugs 12, which act as a support for a plate 13. Connected to the plate by means of the bolt 14 is a long, stiff, closely coiled helical wire, in the 50 form of a spring, the opposite end of which is connected by means of a bolt 16, with a plate 17. The plate 17 acts as a head or mounting for resilient arms 18, four of 55 which are shown, that are adapted to contact the walls of the conduit. The rear guide element just described has the func-

tion of directing and stabilizing the cleaner in its travel through the pipe.

Connected to the periphery of the frame 10, is an annular member 19, having a flared 60 skirt 20. To the overhung flange portion of the member 19 are rigidly connected the spring arms 21, four of which are provided. These arms 21 have a pronounced arcuate 65 form and are of less lateral expanse than the arms 18, this for the reason that they are intended to project into the conduit before it has been cleaned. These arms likewise serve to direct the cleaner or "go-devil," as it is termed in the trade, and maintain it in 70 proper operative relation.

Mounted on lugs or ears 22, integral with the frame 10, are a plurality of bell cranks positioned for oscillation in radial planes. To one arm 23 of each of these bell cranks 75 is connected an impeller blade 24, secured in position by means of a pin 25. These blades as best shown in Fig. 2, overlap and their peripheries are of arcuate form, corresponding to the arc of curvature of the 80 conduit in which the device is to be used.

The other arms 26 of the bell cranks converge to the axis and engage around a projection 27, from a rubber buffer 28. This buffer is carried in suitable flanges 29, 85 formed on a follower 30, slidably mounted within a threaded sleeve 31. Also mounted within the sleeve is a compression spring 32, bearing against the follower and tending to move it and the buffer in an outward 90 direction. A lock nut 33 engages the sleeve and holds it in adjusted position.

Thus it will be seen that the spring and rubber buffer acting against the arms of the bell cranks, swing the blades outwardly 95 against the walls of the conduit. As the liquid moves through the conduit, the force thereof acting on the inclined impeller blades 24 serves to rotate the go-devil and scrape the walls of the pipe.

The parts described are of extreme simplicity and so arranged that they are not likely to become fouled by the stringy particles contained in the paper stock, nor to become unduly worn by the grit thereon. 105 Due to the provision of the spring arms, fore and aft, the device is maintained with the blades in proper transverse relation to the conduit and efficient cleaning action is assured.

An important advantage in the construction is that during the passage of the device

through the conduit, the material displaced from the walls of the conduit always travels ahead of the go-devil; this for the reason that the velocity of the liquid in the conduit is about double that of the go-devil, which results in an increased velocity of the liquid between the blades. Thus any material dislodged from the walls is picked up and carried forward by the liquid.

10 I claim:

1. A liquid impelled tube cleaner, comprising in combination, a frame, forward guide arms rigidly connected thereto, rear guide arms resiliently connected thereto, a plurality of bell cranks pivoted to the frame and mounted for oscillation in radial planes, an impeller blade mounted on one of the arms of each of said bell cranks, and a single spring means acting on the other arms of all of said bell cranks.

2. In a rotary fluid motivated tube cleaner, the combination of a frame, a plurality of curved resilient guide arms rigidly connected thereto, a plurality of rearwardly projecting resilient guide arms connected thereto, with capacity for universal movement, a plurality of arms pivoted to the frame, impeller blades fastened to the arms, and spring means adapted to co-operate with said arms and tending to move the blades outwardly.

3. In a device of the class described, the

combination of a frame, forwardly and rearwardly projecting spring arms connected to the frame, a plurality of cranks 35 pivoted to the frame, and mounted for oscillation in radial planes, blades mounted on one end of said arms, and a single concentric spring acting on the other arms 40 of said cranks and tending to move said blades outwardly.

4. In combination, a supporting frame, forwardly projecting resilient arms connected thereto, rearwardly projecting spring arms, a coil spring constituting the connection between said rearwardly projecting arms and said frame, impeller 45 blades mounted for oscillation relative to said frame, and spring means acting to move said blades outwardly.

5. In a device of the class described, the combination of a supporting plate, having a threaded axial opening, spring arms connected to said plate and projecting forwardly and rearwardly therefrom, cranks mounted on said plate, blades mounted on said cranks, a threaded sleeve mounted in said axial opening, and a spring in said sleeve engaging the cranks to exert a thrust 55 against said cranks.

In testimony whereof I have affixed my signature.

THOMAS R. HAYTON.
